UNITED STATES PATENT OFFICE.

WILLIAM J. STEWART, OF BELLEVILLE, ILLINOIS.

SEWING-MACHINE.

SPECIFICATION forming part of Letters Patent No. 323,968, dated August 11, 1885.

Application filed May 12, 1884. (No model.)

To all whom it may concern:

Be it known that I, WILLIAM J. STEWART, a citizen of the United States, residing at Belleville, in the county of St. Clair and State 5 of Illinois, have invented certain new and useful Improvements in Sewing-Machines, which are fully set forth in the following specification, reference being had to the accompanying drawings, in which—

10 Figure 1 represents a side elevation of a machine embodying my invention, a part of the standard being broken away; Fig. 2, a plan section of the same, taken on the line *x x*, Fig. 1; Fig. 3, a vertical section of the same, 15 through the standard, taken on the line *y y*, Fig. 1; Fig. 4, a bottom plan view of the same, and Fig. 5 a detail view.

15 My invention relates, mainly, to the mechanism for operating the feed devices of a sewing-20 machine.

25 I will proceed to describe in detail the construction and operation of a machine embodying my invention in one practical form, and will then point out definitely in the claims the special improvements which I believe to be new and wish to protect by Letters Patent.

30 As my present invention relates only to a part of the machine, I shall describe particularly only such portions of the entire machine 35 as are necessary to a full understanding of the construction and operation of my improvements.

35 In the drawings, A represents the bed-plate of the sewing-machine, and B the standard, in which the main shaft C is mounted in the usual way. On the main shaft is an eccentric, *c*, to 40 which the upper end of the feed-shaft pitman-lever D is applied by an eccentric-strap, *d*. The feed-shaft E is mounted in any ordinary 45 way on the under side of the bed-plate, and the shuttle-lever F is also mounted on the same side of the bed-plate, being pivoted so as to vibrate as required. The lower end of the pitman-lever D is attached to the crank *c'* on the end of the feed-shaft in the usual manner.

50 In order to support the pitman-lever between the main shaft and feed-shaft, a tubular guide, G, is provided, adapted to receive and embrace the central or body portion of the pitman-lever. This guide is adjustably attached to a shoe or yoke, H, which is pivoted to the standard at some point between the

main shaft and feed-shaft, preferably about half-way. This pivoting of the yoke or shoe will of course permit it to oscillate, thereby 55 providing for a similar movement of the tubular guide, which movement will obviously accommodate the constantly-changing position of the pitman-lever as it is actuated by the eccentric or crank-wheel on the main 60 shaft. This shoe is of yoke form, as shown in Fig. 2 of the drawings, and the guide is arranged within the yoke and fastened to the central portion thereof by means of screws *h*. These screws pass through enlarged holes or 65 slots *h'* in the shoe, and are tapped into the guide, whereby the guide may be adjusted relatively to the shoe. The respective ends of the shoe or yoke are mounted on conical pivot-pins I, set in the sides of the standard, 70 and provided with screw-threads and nuts *i*, by means of which they are adjusted at will. The guide is preferably split, and has flanges *g* at one side, where the tube is split, through which screws *g'* are passed for the purpose of 75 adjusting the guide to fit closely the pitman-lever. Obviously, if the guide and shoe are left in a somewhat loose condition—that is, so as to permit movement in either direction—the turning of the wheel once round, so as to 80 move the pitman-lever up and down, would accurately center the guide; but as this latter piece is rigidly attached to the shoe, and the axial line of the shoe is invariable, being the axial line of the two pivot-pins, it is plain that 85 the guide must be carefully adjusted when fastened to the shoe, so that when the latter is mounted on its pivot-pins the guide will be accurately centered in the direction across the axial line of the shoe, in order to prevent binding in this direction between the guide and the pitman-lever. This adjustment is effectuated by means of the slots *h'*, hereinbefore mentioned. The guide may be centered in the other direction—that is, on the axial line of 90 the shoe—by the movement of the pitman-lever, and may be effected by simply loosening the pivot-pins and then turning the wheel once, which will bring the guide into accurate adjustment in the direction mentioned, the 95 shoe moving slightly one way or the other on its axial line to permit this adjustment. The screw pivot-pins are then set up to the shoe in this position. Now, it is obvious that in 100

the operation of the machine the pitman-lever will move back and forth in the guide, which oscillates back and forth to accommodate the changing position of the pitman-lever, and 5 that this guide will hold the pitman-lever firmly in its proper plane of movement.

In my improvement there is not much wear in the tubular guide, and it will be noticed that there is provision for taking up to compensate for wear, and the adjustment of the 10 guide can always be made so as to prevent any binding strain on the pitman-lever.

In order to give the required vibratory movement to the shuttle-lever F, I provide a finger, K, which is attached at its upper end 15 to the guide-shoe in any suitable manner, and at its lower end is connected to the end of the lever in any suitable manner. In the drawings I have shown this connection made by means of a ball, k, at the end of the finger, which is arranged in a fork, f, at the end of the lever, thus making one kind of universal joint, which is a desirable form of connection between these 20 two parts. Obviously, the oscillation of the shoe, produced by the movement of the pitman-lever described above, will vibrate this finger, which in turn will vibrate the shuttle-lever to produce the usual operation required thereby. It will be understood, of course, 25 that the length of the finger and the fulcrum of the shuttle-lever must be regulated, respectively, so as to produce the degree of movement required for the lever. This finger may be an extension arm made in one piece 30 with the shoe, or it may be made in one piece with tubular guide, or a separate piece attached to the guide or to the shoe, for it is evident that it will receive the same movement whether attached to the shoe or to the 35 guide. In the drawings I have shown it made in one piece with the shoe, and consider this a desirable construction, because cheap and simple.

The construction and arrangement described 40 above will of course necessitate the location of the feed-shaft at one side of the shuttle-lever, which occupies a substantially central position on the under side of the bed-plate. This arrangement places the feed-shaft at one 45 side of a vertical line dropped from the main shaft, and in order to accommodate this ar-

angement the lower end of the pitman-lever is bent, as shown in Fig. 3 of the drawings. I prefer to produce this bend by making the pitman-lever in two pieces, the lower one being bent in the required manner, while the upper one is substantially straight, except at its lower end, where it is turned outward, and is screwed into a socket on the end of the other section. 60

It is plain that as the tubular guide is located about midway of the pitman-lever it will afford a strong and reliable support to the latter, thereby giving it stiffness, in addition to its function of holding the pitman in its 65 proper plane.

It is evident that the improvement may be applied to different varieties of sewing-machines, mechanical changes being made in some instances, perhaps, to adapt the improvement to some peculiarity in the construction of the machine. It is evident, too, that the improvement is not restricted to an eccentric, but is equally applicable to a crank operating the pitman-lever. 70

I do not claim, broadly, an oscillating guide embracing the pitman and operating the shuttle-lever, as the same is set forth in Patent No. 218,141, granted to Henry F. Schleuter, August 5, 1879. 75

Having thus described my invention, what I claim as new, and wish to protect by Letters Patent, is—

1. In a sewing-machine, the combination, with the main shaft and feed-shaft and the pitman-lever connecting the two, of a guide 80 embracing the pitman-lever and adjustably secured to an oscillating shoe mounted on suitable pivots, substantially as and for the purposes specified.

2. In a sewing-machine, the combination, with the main shaft and feed-shaft and the pitman-lever connecting the two, of a guide 85 embracing the lever and adjustably secured to a shoe mounted on suitable pivots, and having a finger arranged to engage with and operate the shuttle-lever, substantially as and for the purposes specified. 90
